(57) **CLAIM**

The ornamental design for an acupressure therapeutic device, as shown and described.

DESCRIPTION

FIG. 1 is a perspective view of an acupressure therapeutic device showing my new design;

FIG. 2 is a front elevation view thereof;

FIG. 3 is a rear elevation view thereof;

FIG. 4 is a first side plane view thereof;

FIG. 5 is a second side plane view thereof;

FIG. 6 is a top plane view thereof;

FIG. 7 is a bottom plane view thereof;

FIG. 8 is a perspective view of the acupressure therapeutic device of FIG. 1 as installed on an example band for placing on a user's right foot;

FIG. 9 is another perspective view of the acupressure therapeutic device of FIG. 8;

FIG. 10 is a front elevation view thereof;

FIG. 11 is a rear elevation view thereof;

FIG. 12 is a first side plane view thereof;

FIG. 13 is a second side plane view thereof;

FIG. 14 is a top plane view thereof;

FIG. 15 is a bottom plane view thereof;

FIG. 16 is a perspective view of the acupressure therapeutic device of FIG. 8 showing the band in an open, unfastened, position;

FIG. 17 is a perspective view of the acupressure therapeutic device of FIG. 8 as positioned on a user's right foot;

(Continued)

FIG. 18 is another perspective view of the acupressure therapeutic device of FIG. 1 as installed on an example band for placing on a user's left foot;
FIG. 19 is another perspective view of the acupressure therapeutic device of FIG. 18;
FIG. 20 is a front elevation view thereof;
FIG. 21 is a rear elevation view thereof;
FIG. 22 is a first side plane view thereof;
FIG. 23 is a second side plane view thereof;
FIG. 24 is a top plane view thereof;
FIG. 25 is a bottom plane view thereof;
FIG. 26 is a perspective view of the acupressure therapeutic device of FIG. 18 showing the band in an open, unfastened, position;
FIG. 27 is a perspective view of the acupressure therapeutic device of FIG. 18 as positioned on a user's left foot;
FIG. 28 is another perspective view of the acupressure therapeutic device of FIG. 1 as installed on an example band for placing on a user's right foot;
FIG. 29 is another perspective view of the acupressure therapeutic device of FIG. 28;
FIG. 30 is a front elevation view thereof;
FIG. 31 is a rear elevation view thereof;
FIG. 32 is a first side plane view thereof;
FIG. 33 is a second side plane view thereof;
FIG. 34 is a top plane view thereof;

FIG. 35 is a bottom plane view thereof;
FIG. 36 is a perspective view of the acupressure therapeutic device of FIG. 28 showing the band in an open, unfastened, position;
FIG. 37 is a perspective view of the acupressure therapeutic device of FIG. 28 as positioned on a user's right foot;
FIG. 38 is another perspective view of the acupressure therapeutic device of FIG. 1 as installed on an example band for placing on a user's left foot;
FIG. 39 is another perspective view of the acupressure therapeutic device of FIG. 38;
FIG. 40 is a front elevation view thereof;
FIG. 41 is a rear elevation view thereof;
FIG. 42 is a first side plane view thereof;
FIG. 43 is a second side plane view thereof;
FIG. 44 is a top plane view thereof;
FIG. 45 is a bottom plane view thereof;
FIG. 46 is a perspective view of the acupressure therapeutic device of FIG. 38 showing the band in an open, unfastened, position; and,
FIG. 47 is a perspective view of the acupressure therapeutic device of FIG. 38 as positioned on a user's left foot.
In the Figures, the broken lines are for the purpose of illustrating environment and form no part of the claimed design.
